Attorney

UNITED STATES PATENT OFFICE.

JAMES SHAY, OF MIDDLETOWN, OHIO.

GATE.

Application filed June 12, 1922. Serial No. 567,789.

To all whom it may concern:

Be it known that JAMES SHAY, a citizen of the United States, residing at Middletown, in the county of Butler and State of Ohio, 5 has invented certain new and useful Improvements in Gates, of which the following is a specification, reference being had to the accompanying drawings.

This invention relates to certain improvements in gates and has relation more particularly to a gate folding or swinging on vertical pivots and it is an object of the invention to provide a gate of this general character having associated therewith novel and 15 improved means whereby the gate may be moved into open position at a point spaced from the gate and preferably under the influence of the weight of a vehicle.

Another object of the invention is to provide a gate having co-acting therewith a novel and improved latch for holding the gate in closed position together with means for releasing said latch to permit the gate to be swung into open position.

25 The invention consists in the details of construction and in the combination and arrangement of the several parts of my improved gate whereby certain important advantages are attained and the device rendered simpler, less expensive and otherwise more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:

Figure 1 is a view in perspective illustrating a gate constructed in accordance with an embodiment of my invention;

Figure 2 is a view partly in elevation and partly in section illustrating in detail certain features of the construction comprised in my 45 improved gate as herein disclosed;

Figure 3 is a horizontal sectional view taken through the structure as illustrated in Figure 2, certain of the parts being indicated by dotted lines;

50 Figure 4 is an enlarged fragmentary view partly in elevation and partly in section illustrating the vehicle operated means for moving the gate into open position and for releasing the latch;

55 Figure 5 is a fragmentary view in per-

spective of the latch for holding the gate in open position; and

Figure 6 is a fragmentary view in plan of the end portion of a rod connected with the cross member or arm of a gate.

As disclosed in the accompanying drawings, a pair of posts 1 are substantially aligned transversely of a roadway and each of said posts is provided at its upper end with an inwardly directed arm 2. Disposed transversely of the roadway and in alinement with the posts 1 is a pit 3 having its upper face closed by the cover 4, said cover being substantially flush with the surface of the roadway.

As herein disclosed, associated with each of the posts 1 is a swinging gate G, said gate being provided adjacent one end portion with a vertically disposed arm 5, the upper end portion of which being pivotally engaged as at 6 with the outer or free end portion of the adjacent arm 2 while the lower end of the arm 5 is continued by the pivot 7 disposed through the cover 4 and terminating in a crank 8 arranged within the pit 3.

The cranks 8 are arranged substantially in quarter relation and, when the gates are in closed position, are disposed at opposite sides of the gates as is clearly indicated in Figure 3. The extremities of the cranks 8 are operatively connected by rod 9 whereby the gates G have unitary swinging movement into either open or closed position. The closing movement of the gates is limited by contact of said gates G with the upstanding stop members 10 carried by the cover 4 of the pit 3.

Fixed to one of the arms 5 adjacent the lower end thereof is a cross arm or head 11 extending beyond opposite sides of said arm 5. Pivots engaged with each extremity of the cross arm or head 11 is a block 12 which is slidably engaged within a slot 14 produced in an end portion of an operating rod 15. Arranged at opposite sides of the block 12 and interposed between said block and the ends of the slot 14 are the springs 16 which operate to absorb the shocks incident to the operation of the gate.

The rods 15 extend in opposite directions along the side of the roadway and have their outer end portions pivotally connected as at 16 with the continuing rods 15'. Each of the rods 15 is slidably disposed through a guide member 17 and the outer or free end

portion of each of the rods 15' is provided with a longitudinally disposed slot 18. Disposed along the side of the roadway adjacent the arms 15 and 15' is a pit 19 closed by the cover 20 and the outer ends of each of the pits 19 is transversely enlarged as at 21, each of said enlarged portions 21 being closed by a cover 22. Depending within each enlarged portion 21 of the pit 19 are the 10 bearings 23 herein disclosed as supported by the cover 22. The bearings 23 have rotatably engaged therewith a rock shaft 24. The extremities of the shaft 24 are continued by the upstanding parallel rock arms 15 and 26, said arms being directed through the slots 27 provided in the cover 22, said slots being of such length to permit the requisite swinging or rocking movement of the arms 25 and 26. The upper or outer 15 end portion of the inner arm 25 terminates in a laterally disposed extension 28 which is directed through the slot 18 in the adjacent rod 15'. The extension 28 is provided with an enlargement or head 29 whereby the rod 25 20 15' is held against displacement with respect to the extension 28.

The upper or outer end of the arm 26 is provided with an inwardly directed elongated extension 30 which is adapted to be 30 engaged by the wheel of a vehicle or otherwise to effect the desired downward movement of the arm 25 to swing the gates G into either open or closed position.

The arms 25 and 26 are normally maintained substantially vertical by the springs 31, each of said springs encircling the shaft 24 with one end portion secured to said shaft as at 32 and with the opposite end portion in contact, as at 33, with the bearing 23.

40 With the gates G in closed position a vehicle traveling toward said gates is caused to pass over an extension 30 with the result that the gates G are caused to swing into open position and after the vehicle has 45 passed between said gates the vehicle is caused to engage the extension 30 at the opposite side of the gate whereby the gates G are returned to their closed position. The gates G are held in closed position by a vertically moving latch 34 co-acting with one 50 of the gates G, the upper end of said latch 34 being beveled to permit said gate to pass thereover when moving into closed position. The latch 34 is slidably disposed through 55 the cover 4 and is carried by an outer end portion of an elongated flat spring 35, the opposite end portion of which being anchored as at 36 to the under surface of the cover 4. This spring 35 serves to normally 60 maintain the latch 34 projected above the cover 4 and in a position to hold the gates G against opening movement.

Overlapping the free end portion of the spring 35 or that end portion of the spring 65 provided with the latch 34 is a rock arm 37

carried by a rock shaft 38 rotatably supported within the pit 3 by the cover 4. The shaft 38 is also provided with a depending rock arm 39 with which is operatively engaged an end portion of a rod 40 also operatively engaged with the horizontal swinging cross lever 41 supported by the cover 4. Also operatively engaged with the lever 41 are the oppositely directed rods 42 diagrammatically indicated by dotted lines in Figure 3. Each of these rods 42 is arranged within a pit 19 and is disposed in a general direction toward the shaft 24 and is operatively connected as at 43 with a rock arm 44 carried by the lower end portion of a vertically disposed rock shaft 45. The upper portion of the shaft 45 is rotatably engaged with an angularly extended portion 46 of a standard 47 carried by the cover 22.

Secured to the upper portion of the rock shaft 45 is a plate 48 disposed in a direction toward the adjacent arm 25 and which plate, when the gates G are in open position and the arm 25 is vertically disposed, extends between the spaced fingers 49 carried by the arm 25. Upon initial swinging movement of the arm 25 in a downward direction under the influence of a vehicle or the like passing over the extension 30 the finger 49 contacts with the plate 48 resulting in a partial rotation of the shaft 45 which, through the instrumentality of the associated rod 42 results in requisite pull being imposed upon the rod 40 to swing the rock arm 37 downwardly and flex the spring 35 sufficiently to retract the latch 34 out of holding engagement with the co-acting gate G so that as the arm 45 continues to move downwardly the gates G will be free to swing into open position. Under normal conditions, that is, with the gates G closed and the arm 25 substantially vertically disposed, the extension 28 of the arm 25 is slightly spaced from the end of the slot 18 in the rod 15' so that the arm 25 will have sufficient movement to effect the release of the latch 34 before the desired endwise movement is imparted to the rod 15' to cause the gates G to swing in open position.

By the time the finger 49 passes free from the plate 48 the gates G have started to swing to their open position and when the finger 49 is free of the plate 48 the spring 35 will project the latch 34 upwardly and at the same time imposes sufficient tension on the rock arm 37 to cause the plate 48 to return to its normal position. After the vehicle or the like has passed over the extension 30 the arms 25 and 26 will return to their normal or substantially vertical position under the influence of the spring 31 and in returning to such position the plate 48 will be caused to extend between the fingers 49 so that the mechanism will be in proper position for another operation.

When the gates G have been swung into their full open position one of said gates passes over the bill 50 of a vertically swinging latch 51. This latch 51 is pivotally supported by a bracket 52 secured to and depending from the cover 20 and the pivoted end portion of the latch lever 51 is continued by an elongated tail extension 53 which overlies an adjacent rod 42. The tail extension 53 provides gravity means for normally maintaining the bill 50 of the latch lever 51 upwardly extended to properly engage the gate G after the same passes over the bill 50 to hold the gates in open position.

With the gates in open position and as a vehicle passes over the extension 30 of the arm 26 the initial movement imparted to the associated rod 42 will cause the upstanding cam 54 carried by said rod to pass under the tail extension 53 resulting in sufficient depression of the bill 50 to disengage from the co-acting gate so that upon the continued downward movement of the arm 25 the gates G will be moved into closed position. After the active finger 49 has passed free of its co-acting bill 48 the rod 42 will be returned to its normal position with the cam 53 in requisite position for a second operation.

From the foregoing description it is thought to be obvious that a gate constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a closure member, a pair of rock arms positioned one upon each side of the closure member, an operative connection between each of the rock arms and the closure member for moving said closure member into either open or closed position, a latch for holding the closure member in closed position, a vertical disposed rock shaft positioned adjacent each of the rock arms, an

outstanding plate carried by each of said shafts, an outstanding finger carried by each of the rock arms for contact with the plate to rock the shaft upon movement of the arm in one direction and an operative connection between each of the rock shafts and the latch for moving the latch out of holding engagement with the closure member upon movement of one of the rock arms in one direction.

2. In combination with a closure member, a rock arm positioned upon one side of the closure member, an operative connection between the closure member and the rock arm to move said closure member into either open or closed position, a latch for holding the closure member in open position, said rock arm having limited movement independently of the connection, a latch for holding the closure member in closed position, a movable member positioned adjacent to the rock arm, coacting means carried by the rock arm and the movable member to impart movement to the movable member during the period the rock arm has movement independently of the connection between the rock arm and the closure member, and a latch for holding the closure member against movement.

3. In combination with a closure member, mounted for movement in either open or closed position, a rock arm, an operative connection between the rock arm and the closure member for moving said closure member to either open or closed position, a latch for holding the closure member in closed position, a latch for holding the closure member in open position, a movable member positioned adjacent to the rock arm, coacting means carried by the movable member and rock arm for imparting movement to the movable member upon movement of the rock arm, and an operative connection between the movable member and both of the holding means for the closure member to move said holding means into inoperative position with respect to the closure member upon movement of the movable member in one direction.

In testimony whereof I hereunto affix my signature.

JAMES SHAY.
